UNITED STATES PATENT OFFICE.

FREDERICK LANE, OF BOSTON, MASS., ASSIGNOR TO THOMAS C. FRENYEAR,
OF EXETER, N. H., AND LLOYD E. RAZEE, OF ATTLEBOROUGH, MASS.

KNOB FOR ELECTRIC GAS-LIGHTING APPARATUS.

SPECIFICATION forming part of Letters Patent No. 311,840, dated February 3, 1885.

Application filed December 26, 1883. (No model.)

To all whom it may concern:

Be it known that I, FREDERICK LANE, of Boston, county of Suffolk, State of Massachusetts, have invented an Improvement in Knobs for Gas-Lighting Apparatus, of which the following description, in connection with the accompanying drawings, is a specification, like letters on the drawings representing like parts.

10 My invention, relating to a gas-lighting apparatus, is shown embodied in an apparatus of that kind in which a gas-valve is opened and an electric spark produced by the movement of a lever supported on the gas-burner, the 15 said lever being usually operated by a small knob or pendant connected with it by a flexible connector—such as a cord or chain—the said knob being within easy reach of the operator. When automatic lighters of this kind 20 are employed, it is often necessary or desirable to operate it in total darkness, as the very object of the apparatus is to avoid the use of matches or torches; and it is at such times very difficult to find the small knob or pendant.

25 In order to obviate this objection, and to render the apparatus much more convenient in use, I have provided it with a self-luminous pendant, shown as composed of a hollow transparent bulb provided at its interior surface 30 with self-luminous or phosphorescent material which is protected by the glass from contact with the fingers of the operator, and is thus kept clean and preserved from wear, the bulb having a cap and a suspending-ring, all as 35 hereinafter specified and claimed.

Figure 1 represents in elevation a gas-lighting apparatus provided with a luminous pendant in accordance with this invention, and Fig. 2 an enlarged sectional view of the 40 pendant detached.

The burner *a*, provided with a gas-cock operated by a ratchet, *b*, and dog or pawl *c*, connected with a lever, *e e'*, may be of any suitable or usual construction, various such burners being well known. The lever *e'* is pro-

vided with the usual spring-electrode, *f*, co-operating with an electrode, *g*, at the side of the burner-tip, and the arm *e* has connected with it, by a chain or other flexible connection, *h*, a self-luminous pendant or knob, *i*, the said pendant being rendered self-luminous or phosphorescent by any of the usual compounds or materials employed for such purpose. The pendant *i* is constructed as shown in Fig. 2, it being composed of a hollow transparent bulb 55 or ball, *i'*, lined upon its interior with a coating, *i''*, of self-luminous material, and provided at its open end or mouth with a metallic cap, *i'''*, having a lug or eye, *m*, for attaching the chain *h*, by which the lighting apparatus 60 is operated. A pendant of this nature is readily visible in the dark, and can be seized by the fingers of the operator without injury to the luminous material, which is protected by the glass or transparent bulb *i'*, and consequently does not become soiled or worn off from the pendant by handling, as would be the case if it were applied to the outside of the said pendant.

I am aware that luminous or phosphorescent 70 material has been applied to knobs, match boxes or holders, and various other articles which are to be used in the dark, and hence I do not broadly claim the use of such material in connection with gas-lighting apparatus; 75 but

I claim—

The pendant *i* for a gas-lighting apparatus, composed of the hollow transparent bulb or ball *i'*, having the internal protected coating, 80 *i''*, of luminous material, the cap *i'''*, and eye *m*, substantially as shown and described.

In testimony whereof I have signed my name to this specification in the presence of two subscribing witnesses.

FREDERICK LANE.
